UNITED STATES PATENT OFFICE.

JOHN P. J. O'NEIL, OF PORTVUE, PENNSYLVANIA.

FOLDING UMBRELLA.

991,451.

Specification of Letters Patent. Patented May 2, 1911.

Application filed September 1, 1910. Serial No. 579,986

To all whom it may concern:

Be it known that I, JOHN P. J. O'NEIL, a citizen of the United States of America, residing at Portvue, in the county of Allegheny and State of Pennsylvania, have invented certain new and useful Improvements in Folding Umbrellas, of which the following is a specification, reference being had therein to the accompanying drawing.

10 This invention relates to folding umbrellas, and the objects of the invention are, first, to provide an umbrella that can be folded into a comparatively small parcel, whereby it can be carried in a traveling bag or the pocket; second, to furnish an umbrella with a sectional stick that can be easily collapsed; third, to provide an umbrella with collapsible ribs that can be folded without injuring the cover of the umbrella; 20 and fourth, to accomplish the above results by an umbrella that is simple in construction, durable, inexpensive to manufacture, and highly efficient.

I attain the above objects by a mechanical 25 construction that will be hereinafter specifically described and then claimed, and reference will now be had to the drawing, wherein:

Figure 1 is a side elevation of the stick 30 and one of the ribs of the umbrella in extended or raised position. Fig. 2 is a horizontal sectional view taken on the line $x-x$ of Fig. 1. Fig. 3 is a similar view taken on the line $w-w$ of Fig. 1. Fig. 4 is an 35 elevation of the stick and rib collapsed or folded, and Fig. 5 is a front elevation of a portion of the stick.

The umbrella stick comprises a handle section 1 and a telescopic tip section 2, the 40 handle section 1 having the lower end thereof threaded, as at 3, for the tubular shank 4 of a handle 5. The upper end of the tip section 2 is interiorly threaded, as at 6, to receive the threaded shank 7 of a detachable 45 tip 8. The upper end of the handle section 1 has a radially disposed guide lug 9 extending into a longitudinal slot 10 provided therefor in the wall of the tip section 2, said lug preventing the section 1 from being 50 accidentally detached from the section 2, also preventing a rotative movement of the upper end of the section 1 within the section 2. The section 2 is retained in an extended position relatively to the section 1 55 by an ordinary stop or clasp 11 carried by

the upper end of the section 1 and adapted to extend under the lower end of the section 2 and retain the section in extended position, the stop 11 being pressed inwardly when the section 1 is to be pushed in the section 2, 60 the stop 11 riding in the slot 10 after the section 1 has entered the section 2.

Mounted upon the upper end of the section 2 is a notch 12 and a cover-cap 13. Connected to the notch 12 is a cord or a 65 flexible connection 14, and connected to the lower end of the cord by a rivet or other fastening means 15 is an outer rib section 16, the cord or flexible connection 14 constituting the inner rib section. The cover-cap 13 in conjunction with the outer end of the rib section 16 is adapted to retain the cover (not shown) upon the umbrella.

Adjustably mounted upon the tip section 2 by a set screw 17 is a runner 18 and pivotally connected to the upper end of said runner, as at 19, is a spreader 20, said spreader having the upper end thereof pivotally connected, as at 21, to a lug 22, carried by the upper and under side of the rib 70 section 16.

To fold the umbrella, the runner 18 can be lowered upon the telescopic tip section 2, but this is not essential, inasmuch that the flexible connection 14 allows the spreader 20 85 and the outer rib section 16 to be swung into parallelism, as shown in Fig. 4. Then by detaching the handle 5, the tip 8, and pushing the section 1 upwardly into the section 2, a small and complete parcel is formed. 90

What I claim is:

A folding umbrella comprising a stick provided with a notch, a rib including an inner and an outer section, the former consisting of a cord and the latter of a metallic tube of greater length than the cord, said cord having its outer end secured to the inner end of the tube and having its inner end fixedly secured directly in the notch, a runner mounted upon the stick, and a 10 stretcher having its inner end pivoted to the runner and its outer end pivoted to the tube at a point between the center and the inner end of the latter whereby when the umbrella is opened the tube will be extended solely by the stretcher, said tube of greater length than said stretcher and said stick of such length with respect to the stretcher that when the umbrella is folded, the tube and stretcher will be parallel throughout with 11

each other with the tube projecting beyond each end of the stretcher and positioned wholly inwardly of the notch thereby positioning the cord entirely between the pivoted 5 end of the stretcher and the notch and parallel with the stick insuring compact folding of the umbrella.

In testimony whereof I affix my signature in the presence of two witnesses.

JOHN P. J. O'NEIL.
